Des. 235,871
Patented July 15, 1975

235,871

HAND CARRIED LIQUID CHEMICAL SPRAYER

James G. Parke, and C. Richard Gerlach, San Antonio,
Tex., assignors to Micro-Gen Equipment Company

Filed Jan. 21, 1974, Ser. No. 435,188

Term of patent 14 years

Int. Cl. D23—01

U.S. Cl. D23—18

FIG. 1

FIG. 2

FIG. 3

FIG. 4

FIG. 5

FIG. 7

FIG. 6

FIG. 1 is a top plan view of a hand carried liquid chemical sprayer showing our new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a perspective view thereof; and

FIG. 7 is another perspective view thereof.

The flexible hose has been broken away in FIGS. 1 through 5 and the shoulder strap has been broken away in FIG. 3 for convenience of illustration and the broken line representation of a man in FIG. 7 is for purposes of illustration only.

We claim:

The ornamental design for a hand carried liquid chemical sprayer, as shown and described.
